UNITED STATES PATENT OFFICE.

CHARLES B. MOORE, OF EVANSTON, ILLINOIS, ASSIGNOR, BY MESNE ASSIGNMENTS,
TO AMERICAN ARCH COMPANY, OF NEW YORK, N. Y., A CORPORATION OF DELA-
WARE.

LOCOMOTIVE-BOILER FURNACE.

1,138,046.

Specification of Letters Patent.

Patented May 4, 1915.

Application filed December 18, 1911. Serial No. 666,351.

To all whom it may concern:

Be it known that I, CHARLES B. MOORE, a citizen of the United States, and a resident of the city of Evanston, county of Cook, and 5 State of Illinois, have invented certain new and useful Improvements in Locomotive-BoilerFurnaces, of which the following is a specification.

My invention relates to improvements in 10 locomotive furnaces and has particular reference to improvements in refractory baffles or deflecting walls, commonly called arches, for the fireboxes of locomotives.

The general objects of my invention are 15 to provide a refractory arch which can be easily and quickly installed in a locomotive firebox; to provide an arch which shall be of light weight and low cost; to provide an arch which shall be easy to repair and parts 20 of which can be readily removed to give access to the flue sheets and side sheets of the firebox to effect necessary repairs thereof and of the stay bolts and to provide an arch of a form that shall materially assist in the 25 admixing of the firebox gases and the ignition of the gases and the fuel particles carried thereby.

A further object of my invention is to provide an improved refractory arch construction 30 having the characteristics above outlined which shall be particularly adapted for the installation of arches in locomotive boiler fireboxes that are equipped with a plurality of circulating or arch supporting tubes.

My invention consists in the several improvements, the various features of construction and the combinations of parts by means 35 of which the above and other objects are attained and all as hereinafter described and particularly pointed out in the appended claims.

My invention will be more readily understood by reference to the accompanying 45 drawings forming a part of this specification and in which;

Figure 1 is a vertical central longitudinal section of a locomotive boiler firebox equipped with a refractory arch embodying 50 my invention; Fig. 2 is a horizontal sectional view of the firebox on the line 2—2 of Fig. 1; Fig. 3 is a transverse vertical section of the fire box on the line 3—3 of Fig. 1; Fig. 4 is a detail transverse section 55 of the arch on the line 4—4 of Fig. 1; Fig. 5

is a section similar to Fig. 4 taken on the line 5—5 of Fig. 1; Fig. 6 is a fragmentary sectional perspective view taken on the line 6—6 of Fig. 2 and showing one of the panel bricks resting in position upon a supporting brick; Fig. 7 is a top plan view of one of the panel bricks; Fig. 8 is a side elevation of the brick shown in Fig. 7; Fig. 9 is an end elevation of the brick shown in Fig. 7; Fig. 10 is a top plan view of one of the locking 60 bricks; Fig. 11 is a side elevation of the locking brick; Fig. 12 is an end elevation of the locking brick; Fig. 13 is a top plan view of the bricks used for spacing the arch from the flue sheet; Fig. 14 is a side elevation of 65 the spacing brick; and Fig. 15 is an end elevation of the spacing brick.

My invention is capable of embodiment in arches which occupy various positions in the firebox and which have different specific 70 functions. I have, however, chosen to illustrate my invention as applied to the formation of a so-called front arch. It should, however, be understood that my invention is not limited to this specific form or position 75 arch.

A so-called front arch usually occupies an inclined position in the forward end of the firebox in contact with or spaced rearwardly 80 a short distance from the flue sheet and it serves to obstruct or baffle the direct flow of the gases of combustion from the fuel bed to the flues and cause them to travel back and forth in the firebox and thereby distribute their heat evenly over the interior 85 surface of the firebox and particularly 90 throughout the length of the crown sheet.

A particular feature of front arches constructed in accordance with my invention, is that in addition to serving as a baffle for the 95 gases of combustion, they serve to break up the strata of gases and thereby aid in commingling and admixing the air and the combustible gases causing substantially complete combustion of the fuel before the gases escape from the firebox through the flues. Front arches constructed in accordance with my invention not only perform the functions above mentioned but also, by reason of their comparative thinness soon attain the maximum temperature of the firebox gases and thereafter assist in the ignition of the gases and the fuel particles carried thereby.

A locomotive firebox as illustrated in the drawings is made up of a flue sheet 2, 100

side sheets 3—3, a crown sheet 4 and a rear sheet 5. The firebox has a grate 6 and the rear sheet is provided with a fuel door 7. Flues 8 lead forward from the flue sheet. 5 The firebox illustrated is equipped with four arch or circulating tubes 9, the same extending from the lower portion of the flue sheet to the upper portion of the rear sheet and serving to increase the circulation of 10 water between the front and rear water legs of the firebox. A particular feature of my invention resides in the fact that the arch is made up or built of but two forms of brick, one form being a span or supporting 15 brick and the other being a panel or cover brick. The supporting bricks 10 are of a length sufficient to span from tube to tube and rest thereon. These bricks are limited in size by the feature that they shall not be 20 too heavy to be readily placed in position upon the tubes and that they shall be capable of being readily passed through the fire door into the firebox, and furthermore that they shall be as large as consistent with the fore- 25 going features, their length being determined as stated by the feature that they shall be long enough to span from tube to tube. I arrange these bricks in transverse rows extending across the firebox. I pro- 30 vide these bricks with reversed interlocking ribs or tongues 11 and sockets 12 at their ends so formed that when these bricks are relatively reversed and placed in position upon the tubes, they interlock with each 35 other and the adjacent bricks of a transverse row thereby maintain each other in position upon the tubes. I build the arch of several of these transverse rows of bricks spaced apart longitudinally upon the tubes and I 40 maintain these rows in their spaced relation by means of cover or panel bricks 13. Looked at from one point of view, the panel bricks may be said to be long enough to fill the spaces between the transverse rows of 45 supporting bricks and overlap at their ends thereon and these panel bricks are provided with transverse abutment shoulders 14 upon their lower faces which are adapted to engage the sides of the supporting bricks and 50 thereby maintain the transverse rows of supporting bricks in proper relative position. In other words these panel bricks are arranged between the rows of supporting bricks and are provided upon their ends 55 with projecting flanges or tongues 15 adapted to rest upon the supporting bricks and thereby hold the panel bricks in proper position. I make the panel bricks of such a size that a number of them are required to 60 fill each of the spaces between adjacent rows of span bricks and I provide the adjacent edges of the panel bricks with half tongues 16 and complementary half grooves 17 whereby these bricks are adapted to interlock with each other at their adjacent edges 65 and thus aid in maintaining each other in position upon the span bricks. While these bricks may be in the form of slabs of an even thickness throughout their extent, I prefer to provide each span brick with a 70 shallow pocket or depression 18 in one face of large extent and with two similar shallow pockets 19 of less extent in its other face. This construction provides each span brick with a cross bar 20 on one face and with 75 end flanges or walls 21 on its opposite face, and I provide the underside of the panel bricks with similar shallow pockets or cavities 22. This formation of arch bricks provides the arch with a plurality of shallow 80 gas mixing pockets and with a plurality of subsidiary gas deflecting surfaces arranged at many adverse angles. The idea of providing the span bricks with shallow pockets in both faces is for the purpose of providing 85 the arch with these shallow gas mixing pockets throughout its under surface regardless of the position in which the span bricks are placed, that is whether one face or the other face is turned downwardly. 90 The arch as a whole rests upon the tubes in substantially a single plane and extends laterally substantially co-equal with the lateral extent of the tubes 9 and I maintain the arch in position transversely in the firebox 95 by means of locking bricks 23 which I arrange between the rows of panel bricks and the side sheets of the firebox. These locking bricks 23 are provided with tongues and 100 grooves upon one edge similar to the tongues and grooves upon the edges of the panel bricks and are adapted to interlock therewith and these panel bricks are preferably of such size that when placed in position with their inner ends in proper contact with the panel bricks they occupy upwardly and outwardly inclined positions with their outer ends resting against the side sheets of the firebox, and for the purpose of making it convenient to fit these bricks properly 105 into position and in proper wedging contact with the side sheets of the firebox, I provide their outer ends with relatively narrow projections or tongues 24 which may be readily chipped off or cut to the proper 110 length so that these bricks wedgingly engage the row of panel bricks with the side sheet and thus lock the arch transversely 115 in the firebox. 120 It is to be noted that the cover bricks are both thin and light and hence add little weight to the arch itself and being thin and light they are quickly raised to a relatively high temperature, or in other words to the maximum temperature of the firebox gases 125 and thereafter they aid in igniting the fuel gases. 130 In building front arches in accordance with my invention, I place a supporting brick in central position upon the tubes and

close to or in contact with the flue sheet and resting upon two of the tubes. This brick is placed in position with the tongues at its ends projecting upwardly and I thereafter 5 complete this row of transverse bricks by placing one of these supporting bricks, which is substantially identical with the brick already placed, at each end thereof interlocking the ends of these bricks together. 10 That is the end bricks are reversed in position relatively to the center brick. When it is desirable to place these bricks at a distance from the flue sheet, I arrange spacing bricks 24' between the lower edges of these 15 supporting bricks and the flue sheet. These spacing bricks are arranged to be supported upon the tubes and each thereof is provided on its underside with a groove 25 which substantially fits the tube and the end of the 20 brick which contacts with the supporting brick is provided with a pair of projecting tongues 26 which are adapted to project beneath the supporting brick, one on each side of the tube and thereby lock the spacing brick in position. The weight of the arch 25 also aids in holding the spacing bricks in position. After the first or lower transverse row of supporting bricks has been placed in position, I arrange a second transverse row of supporting bricks upon the 30 tubes above the first row and spaced therefrom and I hold this second row in position by means of a transverse row of the panel bricks arranged between the first and second 35 rows of supporting bricks. In some instances an arch thus constructed is of sufficient length to cause the proper circulation of firebox gases for the purpose of producing the most economical combustion of 40 the fuel. In other instances it is necessary to extend the arch rearwardly a greater distance. Usually the rear end of the arch is positioned substantially at the middle of the firebox and in the arch illustrated I have 45 shown it as being made up of a third transverse row of support bricks maintained in position by means of a second row of the panel or cover bricks. The arch as thus made consists of a plurality of transverse 50 rows of supporting bricks interlocked together and thereby held against relative longitudinal displacement or separation and these rows of supporting bricks are spaced apart and maintained in their spaced relation by transverse rows of interlocked panel 55 or cover bricks and the arch as a whole is held against transverse movement in the firebox by means of the locking bricks which are wedgingly interposed between the lateral 60 edges of the arch and the side sheets of the firebox. An arch thus constructed is in a sense flexible, for the contacting surface of the various bricks are more or less protected against the cementing action of the slag, 65 which soon unites an arch of ordinary con-

struction into a solid or rigid mass. The arch being thus flexible, can accommodate itself to slight changes of its supports or dimensions of the firebox induced by changes of temperature or pressure without the destruction usual in arches as commonly constructed. 70

It will now be seen that my arch being made up of a plurality of individual bricks which can be readily placed in position, 75 arches can be made or built with the expenditure of comparatively little time or labor. Furthermore, it will be seen that parts of the arch can be easily removed without disturbing the arch as a whole, for 80 the purpose of effecting necessary repairs to the stay bolts or sheets of the firebox. Another advantageous feature of these arches resides in the fact that the supporting bricks are recessed or paneled in both faces and therefore regardless of the face of the bricks, 85 which is turned downwardly, the whole under surface of the arch is provided with subsidiary gas mixing pockets and furthermore as the panel bricks extend between the upper edges of the supporting bricks, and they do not completely fill these spaces, they do in fact provide gas mixing channels or recesses which extend transversely across the 90 entire width of the arch and these transverse channels also aid in the admixing and commingling of the firebox gases. 95

As various modifications of my invention will readily suggest themselves to one skilled in the art, I do not confine or limit 100 my invention to the specific structures herein shown and described.

I claim:

1. A locomotive boiler firebox having a plurality of substantially parallel inclined arch tubes, in combination with a refractory arch body resting on said tubes, said body comprising a plurality of parallel transverse rows of slab-like supporting bricks having complementary grooves and 105 ribs extending across their ends and by which they are interlocked to prevent longitudinal separation thereof, said rows being spaced apart upon the tubes and a plurality of cover or panel bricks interposed, 110 between, resting upon and spacing said rows apart. 115
2. A locomotive boiler firebox having a plurality of substantially parallel inclined arch supporting tubes, in combination with a refractory arch therein supported by said tubes, said arch comprising a plurality of parallel rows of reversible supporting bricks, said bricks being identical in form and having transverse projections and complementary grooves extending across their ends and adapting them to interlock with each other and mutually prevent their relative movement transversely in the firebox, 120 said rows being spaced apart upon the tubes 125 130

and thin cover bricks filling the spaces between the rows of supporting bricks and holding them in their spaced relation.

3. A locomotive boiler firebox having a plurality of substantially parallel inclined water circulating tubes therein, in combination with a refractory front arch resting on said tubes and against the flue sheet, said arch comprising a plurality of transverse rows of identical supporting bricks, each row comprising a center and two end bricks, all of said bricks having transverse vertically extending flanges extending across their ends and complementary transverse grooves arranged to receive the flanges of adjacent bricks, said rows being spaced apart longitudinally on the tubes and relatively thin cover bricks resting on said rows filling the spaces between them and having shoulders engaging the sides of said interlocked bricks to hold the rows spaced apart.

4. A locomotive boiler firebox having a plurality of substantially parallel inclined arch tubes therein, in combination with a refractory front arch resting on said tubes and against the flue sheet, said arch comprising a plurality of substantially parallel transverse rows of supporting bricks resting on said tubes, said bricks being substantially identical in form and each thereof having half thickness horizontal flanges on its ends and vertically extending complementary transverse tongues and grooves extending the length of said flanges adapted when the bricks are arranged in alternate reversed positions to mutually interlock and prevent the separation of the bricks of said rows transversely of the firebox, relatively thin cover bricks interposed between the upper edges of said transverse rows filling the spaces between them and holding said rows separated, and locking bricks wedgingly interposed between the side edges of said arch body and the side sheets of the firebox.

5. In a locomotive firebox, the combination with a plurality of longitudinally arranged inclined water circulating tubes, of a refractory front arch comprising a plurality of rows of firebricks arranged transversely therein and resting on said tubes, said rows of firebricks being spaced apart longitudinally of the firebox and the individual bricks of said rows having complementary hooks and grooves extending across their ends whereby the bricks are interlocked at their ends and thus held against separation transversely of the firebox and transverse rows of thin cover bricks interlocked at their edges to prevent relative vertical movement thereof, said rows of cover bricks being interposed between the rows of supporting bricks filling the spaces

therebetween and holding said rods of supporting bricks separated, and locking bricks wedgingly interposed between the rows of cover bricks and the side sheets of the firebox.

6. A locomotive boiler firebox having a plurality of substantially inclined water circulating tubes therein, in combination with a front arch supported by said tubes and composed of a plurality of substantially parallel transverse rows of supporting bricks spaced apart on said tubes and held in spaced relation by transverse rows of relatively thin cover bricks, said supporting bricks being rectangular in form and substantially identical with each other, each end of each brick having a horizontally extending half thickness flange across its end the same having a vertically extending transverse tongue at its outer edge and provided with a transverse groove adjacent to said tongue, the tongues and grooves of adjacent ends of supporting bricks being adapted to mutually engage each other and prevent the separation of the supporting bricks transversely of the firebox.

7. A locomotive boiler firebox having a plurality of substantially parallel inclined arch tubes therein, in combination with a front arch composed of a plurality of substantially parallel transverse rows of supporting bricks, said rows being spaced apart and held in spaced relation by transverse rows of thin cover bricks interposed between the upper edges of adjacent rows of supporting bricks, said supporting bricks being rectangular and substantially identical in form, each supporting brick being cut away across each end to form half thickness flanges thereat and having a vertically extending transverse rib at its outer edge and a transverse groove adjacent to said rib adapted to receive the complementary rib of the adjacent brick, the alternate bricks in the row being reversed in position and the transverse ribs thereon being adapted to interlock the bricks and prevent the separation thereof transversely of the firebox.

8. A marginal brick for locomotive arches composed of refractory material having a pointed end for engagement with a side sheet and on its opposite end provided with a half tongue and a half groove to interlock with a correspondingly formed arch body brick.

In testimony whereof, I have hereunto set my hand this 5th day of December, 1911, in the presence of two subscribing witnesses.

CHARLES B. MOORE.
